INVENTOR-
Clifford G. King
By George Woodworth
ATTORNEY-

UNITED STATES PATENT OFFICE

CLIFFORD G. KING, OF PROVIDENCE, RHODE ISLAND

BUCKLE

Application filed December 20, 1930. Serial No. 503,695.

My invention relates to buckles, and more especially to friction-lock buckles for use on shoes, although it is capable of application to tongue-buckles and to belt, harness, and other types of buckles.

Shoe buckles are in general attached to the shoe by sewing, and it has been found that the retailer is usually obliged to re-sew them to the shoes because they are not always in the proper position for the particular wearer of a given shoe.

It is therefore the object of my invention to provide a buckle, for example a shoe buckle that may be removably and adjustably attached to the shoe without sewing, and generally, to provide a buckle that may be removably and adjustably attached to a strap by mechanical means.

With this object in view, my invention comprises a U-shaped strap-attaching tongue which is hung on the tongue bar and disposed on the inner face of the buckle frame, extending longitudinally thereof, whereby one of the shoe straps, or in the case of a belt, one of the ends of said belt, may be attached to the buckle by threading said tongue through closely-spaced holes therein. Preferably, the free end of said strap-attaching tongue is provided with means such as a knob or transversely-disposed lug, for preventing the removal of said tongue from said strap by forces exerted in the direction of the length of the tongue.

In one form of my invention the strap-attaching tongue is provided at one end with a resilient clip arranged to spring over the tongue bar, and in the case of a tongue-buckle, such clip may be bifurcated so that the two prongs thereof lie on either side of the usual buckle tongue. In applying my invention to a shoe buckle, I prefer to eliminate the usual buckle tongue and employ buckles of the friction-lock type.

In the drawings which accompany and form a part of this specification—

Figure 1 is a plan view of a friction-lock buckle embodying my invention;

Fig. 2 is a longitudinal section thereof;

Fig. 3 is a plan view with the straps removed;

Fig. 4 is a plan view of the inner face of said buckle;

Fig. 5 is a section taken on the line 5—5 of Fig. 6;

Fig. 6 is a plan view of a tongue-buckle 55 embodying my invention;

Fig. 7 is a section taken on the line 5—5 of Fig. 6, with the straps and tongue removed;

Figs. 8, 9, 10 and 11 are fragmentary 60 views of modifications.

In the particular drawings selected for more fully disclosing the principle of my invention and which are to be taken as illustrative only and not as restrictive, 10 represents the frame of a friction lock buckle consisting in the present instance of a rectangular outer member, the longer sides of which are connected by the inner transverse member 11 which is provided with the oppositely-disposed indentations 12, 12 disposed longitudinally so as to form the centrally-arranged transverse tongue-bar 13. It is to be understood, however, that this particular arrangement is not essential and that the necessary elements only are the frame, the tongue-bar, and the openings 14, 15 between the shorter sides of the frame and the tongue-bar for receiving the strap 16 and frictionally locking the same in the usual well known manner.

In order to attach the buckle to a shoe or to a shoe strap such as 17, without sewing, I provide a strap-attaching tongue 18 hung on the bar 13 in any suitable manner, and in the present instance said tongue is formed with an eye 19 which encloses said bar. The strap-attaching tongue is disposed on the inner face of the frame, extends longitudinally thereof when said buckle is attached to the strap and terminates in a transversely-disposed lug 20. In the present instance the tongue 18 is U-shaped, consisting of a horizontal portion, substantially parallel to the face of the frame when in position of attachment, and two end portions substantially at right angles thereto, the outer end portion terminating in the lug 20, or the ball-shaped knob 20' shown in Figs. 8 and 9, which knob, as shown at 20" in Figs. 10 and

11, may have its forward portion flattened and the inner end-portion terminating in the eye 19 which provides the pivotal connection of the tongue to the buckle-frame.

5 The strap 17, which in the present instance represents one of the straps of a shoe, is provided with closely spaced holes 21, through two of which the tongue 18 is threaded in order to attach the buckle there-to removably and adjustably.

10 The other strap 16 is drawn through the slots 14, 15, tightened, and thus held frictionally to the buckle.

15 It will be noted that if the strap-attaching tongue 14 were not provided with the transverse lug 20, or the knob 20' or 20'', a pull on the strap 17 in the direction of the length of the tongue and away from the eye thereof, would readily draw said strap off said tongue.

20 When a shoe fitted with my improved buckle is purchased by a customer, the buckle may readily be removed from the strap 17 by drawing the free end thereof downwardly and toward the lug, and the buckle then reattached in adjusted position to suit the foot of the purchaser, whereas heretofore the readjustment of such a buckle entailed cutting the stitches and then resewing the buckle to the strap in the desired position.

25 My invention, however, is not limited to shoe buckles or to buckles of the friction-lock type. In Figs. 5, 6 and 7 I show a tongue-buckle of the usual well known type consisting of the frame 22, tongue 23 and tongue-bar 24 to which tongue-bar the U-shaped strap-attaching tongue 25 is removably clipped by means of the resilient bifurcated clip 26 formed on the inner end thereof, said clip being arranged to spring over the tongue-bar on either side of the tongue 23 in a manner that will be obvious.

30 As described above in connection with Fig. 1, the strap 17 which may be a shoe strap, or one end of a belt, is secured to the buckle by threading the tongue 25 through the holes 21 thereof and the free end of the strap 16 is passed through the buckle, tightened and held in position in the usual way by the regular buckle-tongue 23.

35 Having thus described illustrative embodiments of my invention without however limiting the same thereto, what I claim and desire to secure by Letters Patent is:

40 1. A buckle comprising a buckle-frame and a tongue for removably and adjustably attaching said buckle to a strap, said tongue being U-shaped and comprising a portion extending longitudinally of said strap when in position of attachment and two end-portions substantially at right angles to said longitudinal portion, the inner end-portion terminating in means for pivotally attaching said tongue to said buckle-frame, said tongue

45 being constructed and arranged to be threaded through two longitudinally-spaced holes in the end of the strap to which said buckle is to be attached, one of said end-portions being disposed in one of said holes and the other in the next adjacent hole when said tongue is in position of attachment, and means on the outer end-portion of said tongue for preventing the removal of said strap from said tongue by a pull on said strap in the direction of the length of said tongue.

50 2. A buckle comprising a buckle-frame and a tongue for removably and adjustably attaching said buckle to a strap, said tongue being U-shaped and comprising a portion extending longitudinally of said strap when in position of attachment and two end-portions substantially at right angles to said longitudinal portion, the inner end portion terminating in a resilient eye for removably and pivotally attaching said tongue to said buckle-frame, said tongue being constructed and arranged to be threaded through two longitudinally-spaced holes in the end of the strap to which said buckle is to be attached, one of said end-portions being disposed in one of said holes and the other in the next adjacent hole when said tongue is in position of attachment, and means on the outer end-portion of said tongue for preventing the removal of said strap from said tongue by a pull on said strap in the direction of the length of said tongue.

55 3. A buckle comprising a buckle-frame and a tongue for removably and adjustably attaching said buckle to a strap, said tongue being U-shaped and comprising a portion extending longitudinally of said strap when in position of attachment and two end-portions substantially at right angles to said longitudinal portion, the inner end-portion terminating in means for pivotally attaching said tongue to said buckle-frame, said tongue being constructed and arranged to be threaded through two longitudinally-spaced holes in the end of the strap to which said buckle is to be attached, one of said end-portions being disposed in one of said holes and the other in the next adjacent hole when said tongue is in position of attachment, and a lug on the outer end portion of said tongue, said lug extending transversely of said end portion.

60 4. A buckle comprising a buckle-frame and a tongue for removably and adjustably attaching said buckle to a strap, said tongue being U-shaped and comprising a portion extending longitudinally of said strap when in position of attachment and two end-portions substantially at right angles to said longitudinal portion, the inner end-portion terminating in means for pivotally attaching said tongue to said buckle-frame, said tongue being constructed and arranged to

be threaded through two longitudinally-spaced holes in the end of the strap to which said buckle is to be attached, one of said end-portions being disposed in one of said 5 holes and the other in the next adjacent hole when said tongue is in position of attachment, and a knob on the outer end portion of said tongue.

In testimony whereof, I have hereunto 10 subscribed my name this 16th day of December, 1930.

CLIFFORD G. KING.
